UNITED STATES PATENT OFFICE

ARCHIE C. ZIMMERMAN, OF LOS ANGELES, CALIFORNIA

BUILDING CONSTRUCTION

Application filed August 23, 1929. Serial No. 387,886.

This invention relates to building constructions, and more particularly to buildings of the aircraft depot type.

It has been found difficult to properly direct passengers on an air field to proper transport planes without fear of endangering the lives of the passengers. Also, it has been found that where more than one transport plane is to leave on a given schedule, that each transport plane must wait until it is properly loaded and has taken off before the second transport plane can be loaded. The same applies to planes arriving upon an air field.

The present invention has to do with a depot structure which is so arranged as to permit planes to be loaded and unloaded without in any manner interfering with one another, to the end that one plane can be loading or several planes may be loading at the same time, while other planes are unloading and without any interference between the planes. Planes may take off at the same time after loaded or in accordance with the usual practice after a certain duration of time. Such a structure will tend toward fewer accidents, more economical maintenance, relief of anxiety of passengers and prevent passengers from in any manner contacting with movable parts of the transport plane, such as the propellers.

In practicing the invention, I have provided a central concourse having radial tunnels extending therefrom. These tunnels are so arranged that transport planes may be brought in close proximity thereto, the transport planes being arranged in tangential relation to the radial tunnels, to the end that each transport plane can approach the tunnel or leave the tunnel at a tangent and thus avoid any plane at a following or adjacent tunnel.

With the above and other objects in view, the invention consists in the novel and useful arrangement of various elements and features of the invention as shown in the drawing and more particularly pointed out in the claims.

In the drawing:

Figure 1 illustrates a depot in horizontal

section with transport planes grouped thereabout.

Figure 2 is a vertical section of the proposed form of depot, and,

Figure 3 is an enlarged section on the line 3—3 of Figure 2.

Referring to the drawing, I may provide a central or main depot (not shown), which connects with a tunnel *a* beneath the ground surface, which is indicated as *b*. This tunnel is provided for incoming and outgoing passengers and baggage and may be sub-divided for this purpose, in a manner universally adopted for railroad stations. This tunnel connects with a ramp 1 which communicates with the depot *c*. This so-called depot includes a central compartment 2, the wall bounding which is continuous and may be of any form desired such as pentagonal or circular in accordance with necessity. The wall in Figure 1 is pentagonal, although as stated, any shape of wall may be provided. The chamber 2 would be termed a concourse and the tunnel *a* leads directly to this concourse. Extending from this concourse are one or more members *d*. These members are termed tunnels and are used for ingress and egress of passengers and baggage from planes, such as illustrated at *e*. These tunnels include top walls 3 supported by side walls 4 which may rest upon the ground, as shown in Figure 3, and each tunnel is provided with a ramp, as shown at 5. The side walls of the tunnels may be provided with windows 6, as may be desired. Adapted to telescope within certain of the tunnels are extension tunnel members *f*. These members take the same form as the main tunnels and are mounted upon wheels 7 adapted to be supported on trackways 8.

The operation, uses and advantages of the building construction just described are as follows:

I will assume that a group of planes *e* desire to both discharge as well as take aboard passengers and that the planes are illustrated in Figure 1. Each aeroplane approaches the depot under its own power and the pilot directs the plane to a position tangential to one of the tunnels *d*. A station director for aeroplanes would possibly control the traffic

of planes and would indicate to the pilot which tunnel he should select. A station attendant would then move the tunnel member *f* outwardly from the tunnel *d* upon the 5 trackway to a position adjacent the fuselage of the aeroplane and at a place where the door is located so that the passengers could leave therefrom and pass through the tunnels *d* and *f* into the concourse, thence through the 10 tunnel *a* into the main station. A similar arrangement would be utilized for the loading of planes. Certain of the tunnels, as shown at 9, may be termed baggage tunnels and porters could remove grips and other 15 luggage from the baggage compartment of the fuselage and carry the same upon a suitable truck through the tunnel 9 for deposit in the concourse or in the main station. Thus, the passengers would be relieved of 20 the necessity of carrying baggage.

It is assumed in the showing of Figure 1 that the aeroplanes at 10 and 11 are being loaded and after loading, the aeroplanes may take off in the manner indicated by the dotted 25 lines at 12. It will thus be seen that each aeroplane in no manner interferes with either a following or preceding aeroplane that is being loaded or discharged of passengers and baggage. In Figure 1, I have 30 illustrated five aeroplanes in the process of being loaded and unloaded and the arrangement is such that the pilots can immediately take off or land without interference and quite rapidly, and further without in any 35 manner endangering the aeroplane or the passengers. Windows may be provided in the wall bounding the concourse so that passengers may observe the aeroplanes during the loading and unloading thereof without 40 actually being permitted on the field. This is necessary because of rapidly moving propellers which are a constant source of danger to passengers. Furthermore, the average 45 aeroplane due to the draft caused by the propeller creates quite a dust and the concourse and the tunnels prevent this dust from directly contacting with the passengers so that one objectionable feature of aeroplane fields is eliminated by this invention and the 50 passengers enter and leave the aeroplane without in any manner becoming covered with dust and dirt.

Any number of tunnels may be provided in accordance with the needs of each air field 55 and the number of aeroplanes landing or taking off at given times. The arrangement permits an exact schedule to be maintained by the aircraft company. Certain large 60 transport companies are arranging what are known as aerial taxis which will convey aircraft passengers to a given air field for transfer to a transport plane. The arrangement herein depicted will allow an aerial taxi to land, taxi up to the station, the passengers 65 discharged therefrom through one of the

tunnels, and said passengers immediately directed through another tunnel and into the transport plane.

It is obvious that various changes and modifications and variations may be made in 70 practicing the invention in departure from the particular showing of the drawing without departing from the true spirit of the invention.

I claim:

1. In aircraft station construction, a central concourse portion, provided with entrance means comprising a depressed, covered passage-way leading thereto and a plurality of radially arranged tunnels extending 80 therefrom.

2. In aircraft station construction, a central concourse portion, entrance means comprising a depressed, covered passage-way leading thereto, and a plurality of radially arranged tunnel portions provided with telescoping members; said telescoping members providing entrance from the tunnel portions to a vehicle positioned at an angle 90 thereto.

3. In aircraft station construction, a central concourse member, entrance means comprising a depressed, covered passage-way leading thereto, and a plurality of radially arranged tunnels extending therefrom, one 95 of said tunnels having a telescoping portion; said telescoping portion providing an extension from the tunnel to a vehicle to be loaded or unloaded.

4. In aircraft building construction, a central concourse portion, a main entrance tunnel comprising a depressed, covered passage-way leading thereto, and a plurality of tunnels radially extending from the concourse 100 portion.

5. In aircraft building construction, a central concourse portion, entrance means comprising a depressed, covered passage-way leading thereto, and a plurality of radially arranged tunnel members extending therefrom, alternate tunnel members having telescoping portions; said telescoping portions providing extensions from the tunnel members to a vehicle to be loaded or unloaded. 105

6. In aircraft station construction, a substantially circular central concourse member, main entrance means comprising a depressed, covered passage-way therefor, and a plurality of spaced, radially arranged covered passageways for ingress and egress to 110 airplanes and whereby a plurality of airplanes may be positioned tangentially to the passageways to permit different angular approach and departure thereof from any passageway without mutual interference. 115

In testimony whereof, I have signed my name to this specification at Los Angeles, California, this 15th day of August, 1929.

ARCHIE C. ZIMMERMAN. 120
